UNITED STATES PATENT OFFICE.

CHARLES D. LENDER, OF CENTRALIA, ILLINOIS.

PEANUT-WARMER.

No. 800,309.

Specification of Letters Patent.

Patented Sep. 26, 1905.

Application filed June 5, 1905. Serial No. 263,809.

To all whom it may concern:

Be it known that I, CHARLES D. LENDER, a citizen of the United States, residing at Centralia, in the county of Marion and State of Illinois, have invented certain new and useful Improvements in Peanut-Warmers; and I do declare the following to be a full, clear, and exact description of the invention, such as will enable others skilled in the art to which it applies to make and use the same.

This invention relates to improvements in peanut-warmers.

The object of the invention is to provide a device of this character by which peanuts or other commodities may be kept warm and from which the same may be removed in small quantities.

A further object of the invention is to provide means by which the peanuts may be removed from the receptacle containing the same in predetermined quantities.

With the above and other objects in view the invention consists of certain novel features of construction, combination, and arrangement of parts, as will be hereinafter described and claimed.

In the accompanying drawings, Figure 1 is a front elevation. Fig. 2 is a vertical longitudinal sectional view of the warmer. Fig. 3 is a side view and plan of the measuring-scoop drawer removed from the warmer.

Referring more particularly to the drawings, 1 denotes the warmer, which consists of a hollow base portion 2, in which is adapted to be supported a lamp or other heating device 3. In one side of the base portion 2 is formed an opening 4, by which access may be had to the lamp or heating device, said opening being normally closed by a hinged door 5. In the upper portion of the base is formed one or more ventilating-openings 6, which are adapted to be closed by doors 7.

Arranged on the upper end of the base portion 2 is a cover 8, said cover being provided with a central concave portion 9, in which is disposed a chute 10, the outer end of which projects through an opening 12 in the side of the base portion 2, as shown. To the upper side edges of the chute 10 are connected inclined guide-plates 13, which are connected at their upper ends to the upper edge of the concave portion 9 of the cover, as shown. The cover 8 is adapted to be secured to the upper end of the base portion 2 in any suitable manner, but is preferably secured thereto by means of spring-clips 14.

Adapted to slide into the chute 10 is a scoop-drawer 15, said drawer being here shown in the form of a rectangular box, the inner end of which is beveled off on its upper side to facilitate the passage of the nuts into said scoop-drawer when the same is slipped into the chute. The drawer 15 is preferably provided with a transversely-disposed partition by which the size of the same may be regulated to cause the drawer to hold the desired amount of nuts.

Above the cover 8 and supported thereon is a nut-receptacle 16. Said receptacle may be of any suitable construction, but is here shown as and is preferably in the form of a glass globe, which will enable the contents to be readily observed. On the outer side of the base portion 2 of the warmer is secured a bag-receptacle 17, in which bags may be supported in convenient reach of the salesman and from which one bag at a time may be removed without disturbing the others.

In arranging the warmer the nuts are placed in the receptacle 16, and the cover 8 is then placed on the open end of the receptacle, after which the latter and the cover are turned right side up and set onto the base portion 2. The chute 10 will immediately be filled by the nuts from the receptacle 16, so that when the scoop-drawer 15 is inserted in said chute said drawer will be filled with the nuts and when withdrawn will serve as a convenient scoop for placing said nuts into a bag when sold, the scoop being regulated to hold the desired quantity of nuts called for or representing the amount of the purchase.

A peanut-warmer constructed as herein shown and described will be attractive in appearance, convenient in use, and well adapted to the purpose for which it is designed.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. In a peanut-warmer, the combination with a hollow base adapted to contain a heating device, of a concaved cover arranged on

said base, a nut-receptacle adapted to rest on said cover, the latter forming a bottom for said receptacle, an inclined chute arranged in said cover, guide-plates whereby the nuts in said receptacle are conducted to said chute, and a measuring-scoop drawer to remove the nuts from said chute in equal quantities, substantially as described.

2. In a peanut-warmer, the combination 10 with a hollow ventilated, supporting-base adapted to contain a heating device, of a concaved cover arranged on said base, a transparent nut-receptacle arranged on said cover, the latter forming a bottom for said recepta-

cle, a chute arranged in said cover, guide-¹⁵ plates to conduct the nuts from said receptacle to said chute, a scoop-drawer adapted to be slipped into and out of said chute to remove the nuts therefrom in predetermined quantities, and spring-clips for holding the ²⁰ cover in place, substantially as described.

In testimony whereof I have hereunto set my hand in presence of two subscribing witnesses.

CHARLES D. LENDER.
